UNITED STATES PATENT OFFICE.

IRA E. FLETCHER, OF MONTELLO, MASSACHUSETTS.

ROTARY HEEL-SEAT MAKER AND COUNTER-POUNDER

REISSUED

No. 872,617.

Specification of Letters Patent.

Patented Dec. 3, 1907.

Application filed September 26, 1906. Serial No. 336,279.

To all whom it may concern:

Be it known that I, IRA E. FLETCHER, a citizen of the United States, residing at Montello, in the county of Plymouth and State 5 of Massachusetts, have invented an Improvement in Rotary Heel-Seat Makers and Counter-Pounders, of which the following description, in connection with the accompanying drawings, is a specification, like letters on the 10 drawings representing like parts.

The endeavor at present in shoe factories is to secure speed, uniformity and perfection of work, and accordingly I have invented the hereinafter described heel-seat maker 15 and counter shaper or pounder for accomplishing the objects mentioned with relation to the heel part of the shoe.

In carrying out my invention I provide a 20 rotary hammer for pounding and shaping the heel-seat, and in connection with said rotary hammer I provide a pounder or shaper for the adjacent vertical portion of the counter, said counter hammer moving preferably at a slower speed than the rotary heel-seat 25 hammer. The latter hammer is so constructed that its initial blow is light, followed by a smoothing movement and then a hard striking or pressing blow. The result is that the comparatively stiff bends of leather 30 which form the heel-seat are neatly bent over and smoothed down, the light blow serving to bend them down and push the folds forward gently, while the harder pressure draws the leather of the counter, and sets the tacks 35 solid at the same time. This operation proceeds with great rapidity so that the heel-seat is made quickly and with entire uniformity throughout all parts thereof. The rotary hammer not only gives great rapidity of 40 blows but keeps the machine in balance so that it can be run at a high speed with great uniformity of operation.

In the drawing Figure 1 represents in 45 side elevation and partly in section a preferred embodiment of my invention; Fig. 2 is a top plan view thereof.

On a suitable pedestal 1 is mounted a frame or head-piece comprising opposite supporting walls 2, 3 having a cavity or channel 4 between them and supporting a shaft 5 provided with fast and loose pulleys 6, 7. Centrally secured to said shaft is a transverse hammer-head 8 and at the opposite sides thereof are eccentric straps 10 whose rear 55 arms 11 are pivotally connected at 12 with a depending hammer or pounder 13 whose

head 14 curves forwardly in position to operate against the vertical counter portion 15 of a shoe 16, the upper end of said pounder 13 being pivotally mounted at 17 in adjustable 60 blocks 18. The hammer-head 8 rotates in the direction of the arrow Fig. 1 and its forward revolving end is eccentrically curved as clearly indicated at 19 so that the forward engaging portion 20 is at a shorter radial distance from the center 5 than the rear or following end 21.

The shoe and its contained last are mounted on any suitable kind of jack such for instance as a post 22 operated by a foot-treadle 23.

It will be understood that I have shown my invention in its simplest form and have omitted many of the minor constructional details in order clearly to show the essential 75 features. Preferably a work supporting plate or rest 24 is secured to the front lower end of the head apertured at 25 to permit the hammers to operate on the shoe and having an angular bend as shown in Fig. 1 to form a 80 seat or rest-cavity for engaging the shoe and aiding the operator in properly positioning the same.

In use the operator places a shoe on the post 22 and raises the same with the foot lever into position as shown in Fig. 1 whereupon the rapidly rotating hammer 8 delivers a series of quick blows on the projecting edges of the leather and counter about the heel-seat and at the same time a slower series of lateral blows is delivered against the side of the shoe, the result being that the leather and counter of the shoe are rapidly worked into correct position and given the superior formation and shaping which are 95 desired. The rotary hammer not only does its work with great speed but its movement is very uniform inasmuch as the opposite portions of the hammer, or two-hammers-in-one balance each other and also aid by 100 their centrifugal force in giving a precision and uniformity of movement. The shorter end 20 of the oblique ended hammer serves to crush down and form the leather while the middle portion and end 21 press the 105 leather hard down and set the tacks in solidly as required in the best grades of work. By shifting the hammer 14 slightly, its angle and character of blow may be changed, although the character of the blow is regulated mostly by the position in which the operator holds the shoe and the pressure 110

applied through the foot-lever, this being especially the case as to the vertical pressure, or blows from the hammer 8.

While I have herein shown and described my invention in its preferred embodiment I wish it to be understood that I am not limited to the precise details shown.

Having described my invention, what I desire to secure by Letters Patent is:

- 10 1. A heel-seat maker, comprising a heel rest, a rotary hammer above said heel rest for delivering a series of swinging blows to form the heel-seat, combined with a swinging side pounder in the same vertical plane 15 with said hammer below and back of the hammer for simultaneously pounding the counter immediately next to the portion of the heel-seat being crushed down by the hammer, said hammer and pounder being 20 constructed and arranged to strike the leather in directions tending to work the leather forward in the same direction over the edge of the last and inwardly on the heel-seat.
- 25 2. A heel-seat maker, comprising a rotary hammer having a plurality of striking ends extending radially in different directions from the axis of rotation, a work rest for maintaining the shoe in position to receive a 30 series of rapid blows from said hammer at the heel-seat region, combined with a side pounder for engaging the counter adjacent the heel-seat, and means for operating said side pounder to deliver a slower series of 35 blows than said rotary hammer.
3. A heel-seat maker, comprising a rotary hammer for delivering a series of swinging blows to form the heel-seat, a swinging hammer adjacent said rotary hammer for simultaneously pounding the counter adjacent 40 said heel-seat, and a connection from said rotary hammer to said swinging hammer for operating the latter by the former.

4. A heel-seat maker, having an angular heel rest to position the heel of a shoe, a 45 transverse rotary shaft mounted approximately vertically above said heel rest, a radially extending hammer mounted to revolve with said rotary shaft, said radial hammer having the front edge of its outer 50 end beveled and at such a distance from the shaft that when a shoe is in place in said heel rest, the beveled end of the hammer first strikes a light blow which is followed by a forward horizontal, sliding, crushing pressure of the back portion of said outer end of the hammer on the heel-seat of the shoe, an eccentric on said shaft, a laterally movable hammer having its striking end opposite the lower portion of said heel rest to strike 60 against the counter of the shoe, and an eccentric strap from said eccentric to said hammer, arranged to move the latter at each revolution of said shaft to strike a blow against the counter of the shoe. 65

5. A heel-seat maker, comprising a heel rest, a shaft mounted transversely above said rest, a radial hammer fast on said shaft and arranged to swing across said heel rest for giving a long sliding blow and rubbing 70 pressure across the heel-seat of the shoe, a swinging hammer pivotally mounted above said shaft, having its lower end curved forwardly toward said heel rest, and operating means extending from said shaft to said 75 swinging hammer for simultaneously swinging the latter hammer as the first mentioned hammer rotates.

In testimony whereof, I have signed my name to this specification, in the presence of 80 two subscribing witnesses.

IRA E. FLETCHER.
